REFLEX TYPE LOUD-SPEAKER

Filed April 11, 1946

UNITED STATES PATENT OFFICE

2,545,961

REFLEX TYPE LOUD-SPEAKER

Sidney E. Levy, Brooklyn, N. Y., assignor to University Loudspeakers, Inc., White Plains, N. Y., a corporation of New York

Application April 11, 1946, Serial No. 661,430

2 Claims. (Cl. 181—31)

1

This invention has to do with acoustic devices for reproducing or receiving sound, particularly those capable of being used under adverse weather conditions as in outdoor and maritime use or even under water.

When used outdoors, these devices are exposed to moisture and to substances carried by air and moisture. Particularly is this true in maritime work. When mounted on the deck of a vessel they may be completely engulfed by incoming waves and when mounted on a submersible or amphibious craft they may be completely submerged for long periods. Under these conditions, water will penetrate and sometimes fill the sound passages and sound chamber and come into contact with the diaphragm. Salt and other substances will deposit on the diaphragm and impair its operation. In addition when submerged to any considerable depth the diaphragm will be subjected to pressures greater than the relatively light construction of the diaphragm will bear. Also, if the acoustic device is used on a warship or in the vicinity of heavy ordnance, gun fire or the concussion of exploding shells will cause the alternate application of high and low pressures on the diaphragm and this may injure the diaphragm.

Known forms of acoustic devices are unsuitable for use under adverse weather conditions or under water. This is particularly true of the reflex type horn loudspeaker or receiver, which has the advantage of compactness but as presently designed has the disadvantage of having recesses and pockets within the sound passages or chamber which trap water. Moreover none of the present forms of reflex loudspeakers are easily disassembled to permit either drainage of moisture or cleaning of the diaphragm. Usually it is necessary to disassemble the entire unit including the diaphragm driving unit in order to expose the diaphragm. Also, existing means for protecting the diaphragm against high pressure or sudden variation in pressure such as valves in the sound passages are unsuitable for outdoor or under water use since they tend to trap water.

The object of this invention is to overcome these deficiencies. It provides an improved form of loudspeaker and receiver having a novel sound chamber and sound passage arrangement which results in greater compactness, permits moisture to drain readily from the sound chamber and sound passages and in which the diaphragm can be exposed for cleaning by merely removing a cover. The cover serves also as a wall of the sound chamber and sound passage. Another fea-

2

ture of the invention is the provision of novel means for protecting the diaphragm from injury caused by high pressure or sudden variation in pressure.

5 The preferred form of the invention is the special form of reflex type horn loudspeaker and receiver illustrated in the accompanying drawings, in which:

Fig. 1 is a side view in cross-section.

Fig. 2 is a partial side view in cross-section at the point where a lead from the voice coil is attached to a terminal in the clamping ring.

The main structural units are:

(a) the cylindrical body 10 with an inturned flange 11 at one end;

10 (b) the magnetic unit within this body for creating the field flux. Any of the known types of magnetic units providing an annular air gap for a voice coil may be used. As shown the magnetic unit consists of an annular permanent magnet 21, a bottom plate 22, a central core 23 and inner and outer pole pieces 25 and 26 forming an annular air gap 24 therebetween. The magnetic unit is supported by a spider 27 which is connected to the main body 10 by screws 28;

15 (c) the diaphragm having a stiffened central portion 30 which preferably is dome shaped and an annular flange 31 which may be provided if desired with annular corrugations to increase its flexibility. The edge of the annular flange is clamped between clamping ring 32 and annular pole piece 26;

(d) the voice coil 40 wound on an annular core which extends from the diaphragm flange 31 into the annular air gap 24 of the magnet unit;

20 (e) the outer bell-shaped shell 50 forming a narrow annular, gradually expanding doubly reversed sound passage in conjunction with the body 10 and the inverted inner bell 51, the latter being dome shaped at its inner central part 52 to conform to the dome of the diaphragm and to form therewith a sound chamber; and

(f) the dome shaped buffer 60 fixed on the central pole piece top or plate 25 with its outer surface near the diaphragm end, being of the same contour, serves to support the diaphragm when the diaphragm moves inward beyond its normal range of vibration.

25 The cylindrical body 10 is sealed at one end by the diaphragm and at the other by the base portion of outer bell 50. Watertight joints are obtained by use of gaskets 12 and 13 between clamping ring 32 and the inturned flange 11 of the body 10 and between the annular flange 31 of the diaphragm and annular pole piece 26 of the magnetic

unit and by gasket 14 between the lower edge of cylindrical body 10 and the base portion of outer shell 50. The body 10 is attached to the outer bell 50 by any suitable means such as the screws 15. The leads from the voice coil pass between gasket 13 and the diaphragm flange 31 and are connected to terminals 33 anchored in recesses 44 in the clamping ring 32 (see Fig. 2). Clamping ring 32 has a depending flange 34 which fits closely around the outside edge of the diaphragm and of the annular top plate 26, and thus serves to position the voice coil accurately in the air gap. Notches or openings 35 are provided in flange 34 to permit wires from terminals 33 to pass down between the magnetic unit and body 10 to terminals 54 anchored in the base portion of outer bell 50.

The magnetic unit is thus enclosed in a watertight compartment, one wall of which is the diaphragm itself. It is therefore important that the diaphragm should be made of moisture resistant material or of material treated to resist moisture. Many plastics are suitable for this purpose. Preferably a thermo-plastic or thermo-setting plastic is used so that the diaphragm may be molded.

The inner bell 51 serves both as a cover for the diaphragm and as a wall of the sound chamber and sound passages. The bell 51 is spaced from the diaphragm by bosses 58 on the inturned flange 11 of the body 10. These bosses nest in recesses in the bell 51. Screws 56 secure the bell 51 to the body 10. It will be noted that the bell 51 can be easily detached from the assembly by merely removing the screws 56. With the bell 51 removed, the diaphragm is exposed and can be cleaned.

The inner central portion of the bell 51 is shaped to conform to the central dome shaped portion of the diaphragm, and thus provides a dome shaped space between it and the diaphragm. This space is the sound chamber. The sound waves are mainly propagated by the dome shaped portion of the diaphragm, and thus provides a dome shaped space between it and the diaphragm. While the principal function of the annular flange is to support the dome shaped portion and to guide its movement, the annular flange also propagates sound waves to some extent but in diminishing degree from its inner circumference to the point where it is clamped by the ring 32. At a point about one half or two thirds of the distance outward from its inner circumference, the propagation of sound waves becomes negligible, the exact point depending somewhat on the flexibility of the annular rim. It is desirable that the sound chamber be extended to embrace so much of the annular flange as effectively propagates sound waves. It is preferable therefore to have the central dome shaped portion of the inner bell 51 extend over a substantial portion of the annular flange 31.

The exit to the sound chamber is between the lower edge 57 of the dome shaped portion of bell 51 and the annular flange 31. It will be noted that there is thus provided an annular exit along the entire circumference of the lower edge 57 of the dome shaped portion. Since the annular exit has a substantial radius, a comparatively large exit area is obtained with a narrow opening. With a centrally located opening or throat a much wider opening would be required to obtain the same exit area. A narrow opening from the sound chamber makes it possible to use a narrow sound passage. A narrow horn sound passage is desirable because frequency cancellation at bends is less in a narrow passage than in a wide one. With a narrow passage sharper bends can be used and a more compact structure obtained.

An annular sound passage is provided in the space beyond the sound chamber between the ring 32 and body 10 and bell 51 and between the skirt of bell 51 and the skirt of bell 50. In the sound passage so formed, the direction of the sound wave is reversed twice between the exit from the sound chamber and the mouth of the horn. The ring 32, body 10 and bells 50 and 51 are so disposed and shaped that the cross sectional area of the sound passage gradually increases from the sound chamber to the horn mouth in accordance with known horn design principles.

In this structure, when the loudspeaker is mounted with the axis $a-a$ in a substantially horizontal position, any water or moisture penetrating the sound passage and sound chamber will drain freely therefrom. As appears from the drawing, the covered portion, i. e. the portion within the bell 51, of the passage for sound waves through the sound chamber and sound passage proceeds along its entire length in a direction outward from the axis of the diaphragm, thus permitting flow of liquid through this passage. There are no pockets or recesses to trap water.

In order to obtain high fidelity of reproduction, the diaphragm must be of relatively light construction. To protect the lightly constructed diaphragm from injury when it is subjected to high pressure a dome shaped buffer 60 is disposed within the dome shaped portion of the diaphragm. When the diaphragm is subjected to high pressure it will nest against and be supported by the buffer. The buffer should be separated from the diaphragm a distance in excess of the distance of maximum excursion of the diaphragm at peak audio power so as not to interfere with the sound propagating movement of the diaphragm. The buffer, however, should be near enough to the diaphragm to prevent the diaphragm from exceeding its maximum operative movement and by operative movement is meant the movement which the diaphragm can incur without injury. The buffer may be attached to the diaphragm driving mechanism by any suitable means such as a screw 61 coacting with a bracket 62 on the central top plate 26. A groove 63 may also be provided to receive the edge of the buffer and thus to assure that the buffer is properly centered under the diaphragm. It is desirable to provide openings in the buffer such as the slots 64 to minimize the damping effect of confined air between the buffer and the diaphragm. Resilient means such as a rubber ring 65 may be provided to cushion the nesting of the diaphragm against the buffer 60 when the diaphragm is subjected to sudden pressure. When the loudspeaker and receiver is exposed to gunfire or to exploding shells the diaphragm is not only subjected to sudden pressure but also to sudden vacuum. The wave of compression is followed by a recession wave which sucks the diaphragm outward. In this event the diaphragm will nest in and be supported by the dome shaped portion of bell 51. In order to perform this buffer function the dome shaped portion of bell 51 should be separated from the diaphragm an appropriate distance. In determining this distance the same considerations apply as those set forth with respect to the spacing of the buffer 60 from the diaphragm.

What is claimed is:

1. In a reflex-type acoustic device suitable for marine use having a diaphragm, diaphragm driving means and a longitudinal casing around said driving means with the diaphragm disposed in and sealing one opening thereof, the combination

of a bell with its base disposed over the diaphragm to form a sound chamber with a narrow annular exit near the edge of the diaphragm, said bell having a flaring skirt extending toward and around the casing, a second bell with its base closing the other opening in the casing opposite to that sealed by the diaphragm, terminals anchored in the base of said second bell and connected in the interior of the casing to the driving means, said second bell having a flaring skirt encompassing the flaring skirt of the first bell, said casing and bells being so spaced one from another and so proportioned as to form a narrow reversing annular passageway of gradually increasing cross-section and extending along its entire length in a direction outward from the axis of the diaphragm so that liquid will drain freely from the sound chamber and passageway.

2. In a reflex-type acoustic device suitable for marine use as claimed in claim 1, in which said casing and the base of the first bell are provided

with bosses and recesses respectively in nesting relation so proportioned that when nested the base of said first bell will be properly spaced from the diaphragm and means for detachably securing said base of the first bell to the casing so that the diaphragm may be exposed for cleaning merely by removing said first bell.
